(57) **CLAIM**

The ornamental design for an apparatus for delivering a closure element, as shown and described.

DESCRIPTION

FIG. 1 is a perspective view of the apparatus for delivering a closure element, in accordance with an embodiment of the present invention:

FIG. 2 is a side view of the apparatus for delivering a closure element shown in FIG. 1;

FIG. 3 is an opposing side view of the apparatus for delivering a closure element shown in FIG. 1;

FIG. 4 is a top view of the apparatus for delivering a closure element shown in FIG. 1;

FIG. 5 is a bottom view of the apparatus for delivering a closure element shown in FIG. 1;

FIG. 6 is a front view of the apparatus for delivering a closure element shown in FIG. 1; and,

FIG. 7 is a rear view of the apparatus for delivering a closure element shown in FIG. 1.
